UNITED STATES PATENT OFFICE.

ELIAS E. RIES, OF BALTIMORE, MARYLAND, ASSIGNOR, BY DIRECT AND MESNE ASSIGNMENTS, TO RIES & HENDERSON, OF SAME PLACE.

OVERHEAD CONDUCTOR FOR ELECTRIC RAILWAYS.

SPECIFICATION forming part of Letters Patent No. 392,757, dated November 13, 1883.

Application filed September 10, 1887. Serial No. 249,333. (No model.)

To all whom it may concern:

Be it known that I, ELIAS E. RIES, a citizen of the United States, residing at Baltimore, in the State of Maryland, have invented certain new and useful Improvements in Overhead Conductors for Electric Railways; and I do hereby declare the following to be a full, clear, and exact description of the invention, such as will enable others skilled in the art to which it appertains to make and use the same.

In systems of electrical locomotion where the propelling-current is transmitted to the vehicles from a generating-station the motor is mounted upon a wheeled vehicle traveling upon rails, and the current is supplied to the motor either by the rails themselves or by suitable conductors arranged parallel to the track, or by both. If separate conductors are employed, the same are arranged either underground or overhead, and contact-wheels traveling upon such conductors conveying the current to the motor are utilized, and for the successful operation of such systems it is essential that the contact-wheels move with great uniformity and ease upon the line conductors. These wheels are for this reason necessarily light, and as a consequence thereof a derailment of the same frequently occurs, which at once breaks the circuit and stops the motor. If the conductors are placed overhead, it is not practicable to support them throughout their entire length. They are necessarily supported at comparatively few points only, and as heretofore constituted each conductor would bend between the supporting-points and become distorted not only by its own weight, but also under the pressure and the vibrations sustained by the traveling contacts. Moreover, overhead conductors as now constructed are adapted to supply current to a number of locomotives only when the same travel upon the same or upon an adjoining parallel track in the same direction. For this reason in double-track roads two overhead line-conductors had to be provided on account of the impossibility for two traveling contacts to pass each other upon any one of the conductors now used without complicated turn-outs.

It is the object of this invention to overcome the difficulties and objections to the present systems of electric locomotion. I provide

a line-conductor or line-conductors of such cross-section as will render the same self-supporting between the points of support, so that there will be no appreciable bending, elongation, or distortion of the same. My line-conductors will therefore be in fact girders, which can not only support their own weight, but can at the same time sustain the pressure and the vibrations from the traveling contacts without injury. To secure good contact and to prevent the derailment of the traveling contact, I construct the line-conductors with two contact-surfaces facing each other, or with sets of two such contact-surfaces, and in place of the single contact wheel or roller now commonly used I employ two or more of them, constituting a truck which will span the space between said contact-surfaces and will be pressed continuously against the same in opposite directions. In order to permit two contact-trucks to pass each other upon the same line-conductor, a contact-surface or sets of contact-surfaces are provided on opposite sides of one conductor; but in either case they will permit the operation of a double-track road by the use of three line-conductors, one of them constructed in accordance with the fundamental idea of my invention, while the others may more nearly approach the ordinary construction.

My invention also comprises other features which are more or less auxiliary to those here indicated.

It will be understood that other forms of self-supporting line-conductors may be used having provisions for the passage of contact rollers or trucks in opposite directions, and I do not limit myself to the identical construction herein shown and described; but those shown are well adapted to the purposes in view, and are sufficient to illustrate the manifold uses to which my invention may be put. Being of comparatively large cross-section, the line-conductors may be made of iron, steel, or any other metal or alloy of comparatively low conductivity and great strength, whereby the initial cost and the expense of repairs, &c., are considerably reduced, and are especially considerably cheaper than copper overhead conductors of ordinary construction. I apply a thick coat of insulating paint to all parts of

my conductors, with the exception, of course, of the contact-surfaces, and they are properly insulated from the supporting-posts B if the latter are made of metal.

5 My improvements in their most simple form are more especially applicable to systems of electric locomotion wherein one of the rails of the track is used for carrying the current in one direction, while a separate conductor, 10 preferably placed overhead and between the two tracks, is employed for carrying the current in the other direction; but their use is by no means confined to such systems, as will be readily understood by those skilled in the art.

15 In the accompanying drawings, which form a part of this application, several modifications of my improvements are illustrated; but it will be understood that I do not confine myself to the specific constructions herein shown 20 and described, for the same may be widely departed from without departing from the principles embodied therein.

The drawings show, in Figure 1 an end elevation of two electric locomotives upon separate 25 tracks with a common overhead line-conductor between the same; Fig. 2, a diagrammatical view of the tracks, overhead conductor, and contact-trucks of the system illustrated in Fig. 1; Fig. 3, an end view of the common line- 30 conductor with my improved contact-truck thereon; Fig. 4, a side view of the same; Fig. 5, a modified construction of the common line-conductor of such system; Fig. 6, an end view of a system of overhead conductors for a double- 35 track road with contact-trucks thereon; Fig. 7, a plan view of such system and its connections with the generating station; Fig. 8, an end view of a modified form of an overhead conductor for a double-track road.

40 In Fig. 1 two parallel tracks composed of rails A A and A' A', respectively, are shown, with a pillar or post, B, carrying upon its upper end the line-conductor C, which, as hereinafter described is in the form of a self-supporting girder, and which in this instance carries the outgoing current for both tracks. Upon the latter are mounted the wheeled vehicles D D', having each an electric motor, E E', mounted below the platform and geared to 45 one of the axles, as shown.

For each vehicle there is a contact-truck, F, constructed, as hereinafter described, upon the line-conductor, and a flexible conductor, G, suitably connected with the contact-truck 55 which carries the incoming current from the latter to the motor. Leaving the motor at e, the current proceeds by contact-brush e' to one of the axles of the vehicle and by one of the wheels to the track, by which it returns to the 60 generator.

In Fig. 2 the circuit arrangements are shown diagrammatically and can be easily traced. The two tracks A A A' A' are arranged as in Fig. 1 with the line-conductor C between the 65 tracks. The positive terminal from the generating-station is connected with the line-con-

ductor and the negative terminal is branched, and one of the branches is connected to the inner rail of one and the other branch to the inner rail of the other track. If, now, an electric 70 locomotive having the arrangements shown in Fig. 1 is placed upon one of the tracks, the current will proceed from the positive terminal of the generators or generator to the line-conductor C, and by the respective contact-truck F and flexible conductor G to the motor. From the motor the current will continue by the path traced with reference to Fig. 1 to the inner rail of the track and will return through the latter to the generator or generators. Precisely the same course will be taken by the current through another locomotive placed 80 upon the adjoining track. The circuits are thus in multiple-arc branches, and it is clear that a number of locomotives may at the same 85 time be propelled upon each track.

The line-conductor C is constructed as shown in Figs. 3, 4, and 5. Its general shape is that of a double T-girder with the central stem of one T forming the continuation of the central 90 stem of the other. Thus four contact-surfaces, c c c c, are furnished by each line-conductor of the form here shown, each contact-surface being the end of a lateral stem of the double T, so that on each side of the central stem or web 95 d there are two contact-surfaces facing each other. This line-conductor may be made of any suitable material, and may be cast or rolled in one piece, as shown in Fig. 3; or the central web, d, may be made separately, and may 100 be united with the lateral stems by bolts, as shown in Fig. 5, or in any other suitable manner. The main object of this construction is to render the conductor self-supporting and to allow the passage over the same of two contact-trucks in opposite directions. The contact-truck used in connection with this form of line-conductor is constructed as shown in Figs. 3 and 4. There is a truck-frame composed of two plates, F' F', each having two 105 stationary bearings for the journals of grooved contact-rollers f f, and one sliding bearing, f'', for the journal of a grooved contact-roller, f''. Journal-bearing f', and with it the roller f'', is seated upon a spring, s, where 110 by roller f'' is forced away from the line which joins the axles of rollers f f. This truck is placed upon the line-conductor in such manner that the grooves of rollers f f are engaged by the lower contact-surface, c, of the line-conductor, while the groove of roller f'' is engaged by the upper contact surface, c, of the line-conductor. In this position of the contact-truck the spring s is compressed, so that the rollers are forced firmly against the contact-surfaces, which safely engage the grooves 115 of the rollers, whereby a derailment of truck is made practically impossible. It will be understood that with this construction of contact-truck it is easy to remove the same from 120 the line-conductors without difficulty. All that is necessary is to compress the spring s

sufficiently to disengage the grooves of the wheels or rollers from the contact-surfaces. The flexible conductor G is detachably connected with the contact-truck by a sleeve, f^3 , 5 fast upon one of the plates, F', and provided with clamp screws, as indicated in the drawings. By preference this sleeve f^3 is at an angle to the plane of plate F' and points toward the line of travel of the locomotive, whereby 10 the flexible conductor G, which will bend to the natural curve of flexure, will proceed from the sleeve without a violent angular bend.

In Figs. 6 and 7 a complete system of overhead conductors, with appropriate contact-trucks, is shown as applied to a double-track road. In this system the track is an ordinary railway with the rails in section, which need not be electrically connected, since the current is supplied to the motors entirely by the overhead conductors. The connection of the generator with these conductors is identical with the connections shown in Fig. 2, except that for the inner rails, A A', the auxiliary line-conductors are substituted. These auxiliary conductors C are constructed as shown in Fig. 6. They are in effect like the principal line-conductor, C, with the lateral stems and contact-surfaces on one side of the central stem omitted.

30 The three line-conductors are secured with their heads to plates H, of insulating material, whereby they are held apart at proper distances, and the whole system is mounted upon posts B in the same manner as the single-line conductor in Fig. 3. The contact-trucks for this modified system are composed each of two trucks of the kind described with reference to Figs. 3 and 4, which are joined by a block, f^4 , of insulating material, secured to a 35 adjacent plates F' F' of the two sections.

40 The sleeve f^3 , for the reception of the flexible conductor G, is secured to block f^4 , and two insulated wires, $w w$, embedded in the cable, are connected one to each of the adjacent plates F', the outer ends of these wires being connected with the motor in the usual manner. The outgoing current from the generator passes to the central line-conductor, and by one half of the twin truck and one of the 45 wires w to the motor. It then returns from the motor by the other wire w and by the other half of the twin truck to one of the auxiliary line-conductors back to the generator.

A modified form of overhead conductors for 55 a double-track road is shown in Fig. 8. In this case the auxiliary conductors are dispensed with, the line-conductor being constructed with two T-irons, having their central stems connected mechanically, but insulated from each other electrically by means of an insulating-plate, x , as shown. The generator is in this form of line-conductor connected with the two T-irons, as indicated by the plus and minus sign, and trucks constructed substantially like those shown in Figs. 3 and 4 are used for carrying the current to the mo-

tors, the only difference being that in this case contact-wheel F^2 is mounted in insulating-bearings, and is provided with an extended shaft, to which one of the flexible conductors 70 is connected, or contact-trucks constructed substantially like those shown in Fig. 8 may be used.

Having thus fully described my invention, what I claim, and desire to secure by Letters 75 Patent of the United States, is—

1. In an electric railway, the combination of a line-conductor extending parallel with the road and having pairs of contact surfaces, each contact-surface of a pair facing the other, 80 with contact-trucks, each mounted to engage with a pair of contact-surfaces, substantially as described.

2. In an electric railway, the combination of a system of line-conductors extending parallel with the road and having pairs of opposed contact-surfaces, with a contact-truck for each pair consisting of three grooved rollers engaging the contact-surfaces and a spring for forcing the rollers into contact with the 90 contact-surfaces, substantially as described.

3. In an electric railway, the combination of a charged line-conductor extending parallel with and between the inner rails of a double track and having pairs of opposed contact-surfaces, with a contact-truck for each track deriving current from each pair of contact-surfaces of the same line-conductor, an electric locomotive upon each track, and a flexible conductor from each contact-truck to its respective locomotive, substantially as described.

4. In an electric railway, the combination of a charged line conductor extending parallel with and between the inner rails of a double track and having pairs of opposed contact-surfaces and an auxiliary line-conductor for each track, also having a pair of opposed contact-surfaces, with a contact-truck for each track having contact-wheels which are insulated from each other, bearing, respectively, 100 upon the principal line-conductor and upon one auxiliary line-conductor, substantially as described.

5. In an electric railway, a girder or channel conductor formed of two longitudinal sections, each provided with flanges or contact-surfaces facing those of the other, contact-trucks adapted to travel upon said flanges and be retained thereby, and provided with collecting devices and a suitable source of electricity in circuit with the conductor.

6. In an electric railway, the combination, with the longitudinal line-conductor having one or more conducting channels or ways, of the contact-truck adapted to travel therein 125 and having upper and lower contact-wheels or collecting-surfaces, and circuit-connections from the contact-surfaces of the truck to the terminals of a moving translating device, substantially as described.

7. In an electric railway, an elevated conductor system comprising a line of posts

planted at intervals midway between the rails of a double-track railway, a continuous self-supporting conductor extending from post to post along the line of way and provided with a collector-channel at each side of its center line, and contact trucks or trolleys traveling within said collector-channel, those at one side in a direction opposite to those on the other, and flexible connection between the trucks

and the vehicles traversing the railway, substantially as described.

In testimony whereof I affix my signature in presence of two witnesses.

ELIAS E. RIES.
